Primary Examiner — Melanie Pellegrini(74) *Attorney, Agent, or Firm* — Dickinson Wright PLLC(57) **CLAIM**

We claim the ornamental design for gemstone, substantially as shown and described.

DESCRIPTION

FIG. 1 is a top perspective view of a gemstone; FIG. 2 is a bottom perspective view of the gemstone of FIG. 1;

FIG. 3 is a front view of the gemstone of FIG. 1;

FIG. 4 is a back side view of the gemstone of FIG. 1;

FIG. 5 is a left side view of the gemstone of FIG. 1;

FIG. 6 is a right view of the gemstone of FIG. 1;

FIG. 7 is a top view of the gemstone of FIG. 1; and,

FIG. 8 is a bottom view of the gemstone of FIG. 1.

The broken lines in the drawings illustrate portions of the gemstone that form no part of the claimed design.

1 Claim, 5 Drawing Sheets---
